UNITED STATES PATENT OFFICE.

HUGH D. CLARK, OF COLUMBUS, OHIO.

DESIGN FOR A BASE FOR GRAVE-VAULTS.

48,928.

Specification for Design.

Patented Apr. 25, 1916.

Application filed April 6, 1914. Serial No. 830,056. Term of patent 7 years.

To all whom it may concern:

Be it known that I, HUGH D. CLARK, a citizen of the United States, residing at 1117 Oak street, Columbus, Franklin county, Ohio, have invented a new, original, and ornamental Design for a Base for Grave-Vaults, of which the following is a specification, reference being had to the accompanying drawing, forming part thereof.

The figure is a perspective view of a base for grave vaults, showing my new design.

I claim:

The ornamental design for a base for grave vaults, as shown.

HUGH D. CLARK.

Witnesses:

C. C. SHEPHERD,
A. L. PHELPS.
